UNITED STATES PATENT OFFICE.

THOMAS R. CALLAN, OF ODELL, NEBRASKA.

DESIGN FOR A TOOL-RACK.

SPECIFICATION forming part of Design No. 23,104, dated March 6, 1894.

Application filed February 5, 1894. Serial No. 499,205. Term of patent 7 years

To all whom it may concern:

Be it known that I, THOMAS R. CALLAN, a citizen of the United States, residing at Odell, in the county of Gage and State of Nebraska, have invented a new and original Design for Tool-Racks, of which the following is a specification.

The invention relates to a new and original design for tool racks.

- 10 The object of the present invention is to provide an ornamental and attractive tool rack; and the essential feature resides in a rack having a vertical polygonal body presenting longitudinal rectangular faces and
- 15 provided at its ends with cones rising from polygonal bases, said rack having an angular door and provided with upper and lower annular series of triangular brackets arranged in pairs.
- 20 The figure of the drawing is a perspective view of a tool rack showing my new and original design.

Referring to the drawing, 1 designates a vertically disposed polygonal body presenting

similar rectangular faces 2 and having a central vertically disposed angular door 3. Each end of the body is provided with a tapering cone 4 rising from a regular rectangular base and presenting triangular faces.

The rack is provided with upper and lower 30 annular series of brackets 5 located on the rectangular faces 2 near the ends of the same. The brackets 5 are triangular, and are arranged in pairs, and have scalloped upper edges.

It will be apparent that the revolving tool rack presents an ornamental and attractive appearance.

What I claim is—

The design for a tool rack herein shown 40 and described.

In testimony that I claim the foregoing as my own I have hereto affixed my signature in the presence of two witnesses.

THOMAS R. CALLAN.
